UNITED STATES PATENT OFFICE.

EUGENE FOURNIER, OF PARIS, FRANCE.

VAPORIZING APPARATUS.

SPECIFICATION forming part of Letters Patent No. 760,784, dated May 24, 1904.

Application filed November 27, 1903. Serial No. 182,900. (No model.)

To all whom it may concern:

Be it known that I, EUGENE FOURNIER, a citizen of the Republic of France, and a resident of Paris, France, have invented certain new and useful Improvements in or Relating to Liquid-Vaporizing Apparatus, of which the following is a specification.

This invention relates to an apparatus for the instantaneous evaporation of liquids, and is particularly suitable for sanitary and disinfecting purposes. It is constructed in such manner that the evaporation takes place without the vapors produced being in any way modified or decomposed or their nature altered and at a very small cost.

An apparatus according to this invention is illustrated, by way of example, in the accompanying drawing, in which it is shown in vertical section.

20 The apparatus is mainly constituted by a vaporizer-tube *a* in the shape of a coil of a truncated-cone shape, arranged so as to be completely protected from contact with the atmospheric air in a casing *b*, also having the shape 25 of a truncated cone and constituted by two walls *c* *d*, arranged concentrically one within the other. The inner wall *c* is directly heated by means of any suitable gas, petroleum, alcohol, or other burner, and is provided on its 30 inner face (as regards the casing *b*) with a spiral rib *e*, extending round the said wall and constituting a channel in which are located the corresponding windings of the coil *a*, which are thus separated from each other by the rib *e*. 35 This rib *e* being in contact with the corresponding portions of the coil *a* transmits to it by conductivity the heat supplied to the wall *c* by the heating apparatus used.

In order to avoid any oxidizing of the metal 40 constituting the coil *a*, the latter is completely protected from contact with the atmospheric air by the casing *b*, which for that purpose is filled with very fine sand or any other suitable material, which fills in all the spaces round the 45 coil *a*.

The inner face of the outer wall *d* is prefer-

ably provided with asbestos packing *f* to prevent waste of heat.

The tube *c* is provided with a flange *g*, to which are secured feet *h* of suitable height 50 supporting the whole of the apparatus at a desired level above the heating apparatus, which should be placed in such way as to direct the whole of the heat to the center of the truncated-cone chimney formed by the wall *c* and 55 to cause it to act directly on the said wall, so as to raise its temperature to and maintain it at the desired heat. The truncated-cone shape given to the apparatus has for its object to concentrate the heat to a sufficient extent before 60 allowing the hot gases to escape at the top. The outer wall or tube *d* is provided at the bottom with a corresponding flange *i*, arranged outside and applied and secured by means of bolts to the flange of the wall *c*, constituting the 65 shoulder or base of the apparatus.

The casing *b* is closed at the top by a cover *j*, applied to the corresponding ends of the walls *c* and *d*, the latter being provided with an outside flange *k*, to which the cover is secured by means of bolts. The cover is provided in the center with a branch *l*, forming an outlet for the hot combustion-gases, and a bend *m* for giving a suitable direction to the gases can be connected to the said branch. 75

The liquid to be evaporated is preferably introduced through the lower end of the coil *a*, which for that purpose is extended outside the apparatus by means of a pipe *n*, to which is connected the supply-pipe for the liquid to 80 be evaporated. The escape of the vapors takes place at the top of the coil *a*, which is prolonged to that end outside the apparatus at *o*, at which place the outlet-pipe for distributing the vapor is connected to it. 85

The working of the apparatus is too simple to require any special description, and it is sufficient to mention that the apparatus having been previously heated to the desired temperature this temperature is maintained during the time that the liquid is introduced into the coil *a* under the desired pressure. The 90

casing *b* forms a kind of a reservoir of heat which greatly facilitates the heating effect. As already stated, it prevents the metal of the coil from getting oxidized, and consequently 5 insures perfect evaporation of the liquid.

What I claim as my invention, and desire to secure by Letters Patent, is—

An apparatus for the vaporization of liquids, particularly intended for sanitary and 10 disinfecting purposes comprising a closed double-walled truncated-cone casing provided interiorly with a spiral rib, a spiral tubular coil for the liquid to be vaporized in the channel

formed by the spiral rib an outlet at the top for conveying away the products of combustion, and an inlet branch for the introduction of the liquid to be vaporized and a vapor-outlet branch substantially as described. 15

In testimony whereof I have signed my name to this specification in the presence of two sub- 20 scribing witnesses.

EUGENE FOURNIER.
